UNITED STATES PATENT OFFICE.

CLINTON E. WOODS, OF CHICAGO, ILLINOIS.

DESIGN FOR A FRAME FOR DYNAMOS.

SPECIFICATION forming part of Design No. 23,743, dated October 23, 1894.

Application filed June 11, 1894. Serial No. 514,253. Term of patent 14 years.

To all whom it may concern:

Be it known that I, CLINTON E. WOODS, a citizen of the United States, residing at Chicago, in the county of Cook and State of Illinois, have invented and produced a new and original Design for the Frame of a Dynamo-Electric Machine, of which the following is a specification.

My invention relates to the form of a frame for dynamo electric machines such as are used for generating current or for operation as motors.

Figure 1 is an end view of the machine. Fig. 2 is a perspective view of the same.

Like parts are indicated by like letters in both the figures.

A is the sub-base of the machine substantially round or slightly elliptical.

B is the base ring superimposed upon the

sub-base and provided with the standards C 20 C as shown.

D. D are two cylinders rising from the bed or base the two ends of which are connected crosswise by metal pieces shaped as shown.

The essential feature of the design em- 25 braces, therefore, a substantially round or elliptical base with curved standards thereon, two cylindrical portions rising from the bed or base and connecting metal portions at the top and bottom of said cylinders. 30

What I claim as my invention is—

The design for the frame of a dynamo electric machine substantially as herein shown and described.

CLINTON E. WOODS.
